UNITED STATES PATENT OFFICE

BEN HILL ROBERTS, OF CORDELE, GEORGIA

SELLING MACHINE

Application filed September 6, 1929. Serial No. 390,832.

This invention relates to shelling machines and is designed primarily for shelling peanuts.

It is an object of the invention to provide a novel form of concave with which cooperates a cylinder having means thereon for cooperation with the shells of the peanuts whereby, during the rotation of the cylinder, the peanuts will be kept under a lateral agitation as well as an annular movement and will be caused not only to break upon the concave but also to roll one against the other and thereby facilitate the shelling action.

Another object is to simplify the construction of the body portion of the machine and also of the cylinder so that the several parts thereof can be formed readily and easily assembled.

A further object is to provide a concave which will not become clogged by the peanuts but will be self-clearing.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a front elevation of the machine, a portion of one of the doors being broken away.

Figure 2 is a top plan view.

Figure 3 is a vertical longitudinal section through the machine.

Figure 4 is a section on line 4—4, Figure 3.

Figure 5 is a section through one end portion of the machine on line 5—5, Figure 4.

Figure 6 is a transverse section through one of the slats of the cylinder, a portion of the

cylinder head being shown, said view being on an enlarged scale.

Figure 7 is an enlarged transverse section through one end portion of one of the slats of the cylinder and through the adjacent portion of the head.

Figure 8 is a detail view of one of the heads of the concave.

Referring to the figures by characters of reference, 1 and 2 designate oppositely disposed but duplicate heads of the casing each formed preferably of a casting having an upwardly projecting extension 3 formed with opposed diverging edges. An inwardly extending annular flange 4 is formed at the margin of each of the heads 1 and 2 and each of these flanges cooperates with the extension 3 on its head to form a circular recess 5 having a concentric circular opening 6 at the center thereof.

Bolted to the outer faces of the heads 1 and 2 are the upper ends of standards 7 which serve to close the openings 6. The bottom portion of each of these standards has a foot 8 adapted to rest on a supporting surface and extending laterally from each standard near its upper end is a bearing member 9 adapted to cooperate with a removable cap 10 for housing one end of a shaft as hereinafter explained.

As heretofore pointed out the heads are oppositely disposed and are duplicates. The upwardly diverging edges of the extensions 3 have bolted to them plates 11. Each plate is folded as shown particularly in Figure 4 and one edge portion of each plate forms a depending apron 12 that extends downwardly between the upper portions of the heads 1 and 2.

The other end portion of each plate is bent laterally and curved downwardly as shown at 13 and is bolted to the upper portions of the heads 1 and 2.

The lower portions of the heads 1 and 2 are connected by transversely curved plates 14

bolted thereto. These plates are spaced apart to provide an outlet 15 and hingedly connected to each of the plates 14 is a guide plate 16. These guide plates can be adjusted relative to each other so as to control the delivery of shelled peanuts through the outlet 15.

To the upper edges of the plates 14 are hingedly connected arcuate doors 17 and when these doors are shut they rest against 10 the peripheries of the heads and extend close to the plates 11. Any suitable means, such as buttons 18 or the like carried by plates 11 can be used for fastening the doors 17 in closed positions.

15 The concave of the machine is made up of segmental end and intermediate heads 19 each of which has inwardly extending tapered spacing fingers 20 forming a series defining a substantially circular opening 21. Seated 20 in these heads 19 and spaced apart by the fingers 20 are flat bars 22 the inner edges of which are flush with the inner ends of the fingers.

25 Bars 22 are adapted to be maintained in the spaces provided for them between fingers 20 by circular inwardly extending flanges 23 formed on the end heads 19 and extending around the central openings 6 in these heads.

30 The ends of the heads 19 of the concave abut against the depending aprons 12 so that the upper strips or bars 22 cooperate with these aprons to form a continuation of the hopper produced by plates 11 and the extensions 3.

35 As before stated the bearings indicated at 9 and 10 engage the end portions of a shaft. This shaft has been indicated at 24. To the shaft are secured the heads 25 of the cylinder that cooperates with the concave. In addition to the end heads there is provided an intermediate head 26 and fastened on these heads are parallel strips 27 formed of metal and arranged close together. On the outer surface of each strip are formed crossed ribs 45 28 constituting agitating means as herein-after pointed out. The strips are fastened to the heads by any suitable means, such as countersunk bolts 29 seated therein as shown in Figure 7.

50 The periphery of the cylinder is concentric with the concave but is spaced therefrom a sufficient distance to permit the shells of peanuts to gravitate around the cylinder. Any unbroken shells entering between the cylinder and the concave, however, will be cracked and broken because of the restricted space through which they must pass.

55 For the purpose of supporting the intermediate head 19 of the concave an arcuate member 29 is extended around the bars 22 and abuts against the aprons 12. The intermediate head 19 is attached to these strips and the plates 11 and 14 are also attached to it.

65 In practice the shaft 24 is rotated by any

suitable means provided for that purpose. For example a pulley 30 can be secured to this shaft for receiving motion from a belt.

The peanuts to be shelled are placed in the hopper provided by the extensions 3 and the plates 11 and will gravitate between the aprons 12 and the upper slats 22 into position between the rotating cylinder and the stationary concave. The crossed ribs 28 on the cylinder will cause the peanuts to be 70 agitated longitudinally of the cylinder as they are carried therewith over the inner edges of the slats or bars 22.

75 As a result of the foregoing the peanuts will be caused to rub against each other and become crushed not only by pressure of one against the other but also because of pressure between the cylinder and the slats of the concave. Consequently the shells will be quickly 80 broken up into small pieces which will fall 85 freely through the spaces between the slats or bars 22. These spaces are also large enough to allow the kernels of the nuts to pass freely. As the spaces diverge outwardly because the fingers 20 are tapered in- 90 wardly, there is no danger of any of the shells or kernels becoming wedged in the spaces. Instead, these spaces will be kept 95 clear, and consequently, the broken shells and the hulled kernels will be able to flow without hindrance into the casing formed by the doors 17 and plates 11 and 14 and thence through the outlet 15.

What is claimed is:

1. A sheller including a casing having 100 heads and connections between the heads, outer and inner concentric flanges on the heads, a concave including heads secured between the flanges, each head having inwardly extended tapered fingers, flat slats seated between the fingers and lapping the inner flanges on the heads and adapted to be retained by said flanges between the fingers, and a cylinder mounted for rotation within the heads of the casing and partly surrounded by the concave.

105 2. A shelling machine including standards, heads secured to the standards and having openings closed thereby, outer and inner concentric flanges on each head, connections between the heads cooperating therewith to provide a casing, a concave having heads seated between the flanges and formed with inwardly extending tapered fingers, slats seated between the fingers and diverging outwardly, said slats being retained in engagement with the fingers by the inner flanges on the heads of the casing, a hopper opening downwardly between the uppermost slats of the concave, and a cylinder mounted for rotation within the heads of the casing and extending longitudinally of but spaced from the concave, said cylinder including heads, strips secured thereto, and outstanding 115 120 125 130

crossed agitating means carried by each strip.

3. In a shelling machine the combination with a concave including spaced slats, of a cylinder partly surrounded by the concave, and crossed outstanding ribs integral with the cylinder and disposed at acute angles to their planes of rotation.

In testimony that I claim the foregoing as
10 my own, I have hereto affixed my signature.

BEN HILL ROBERTS.
